UNITED STATES PATENT OFFICE

116,078

DESIGN FOR AN ENGINE DRIVEN ELECTRIC GENERATOR UNIT

Joseph H. Jacobs, Minneapolis, Minn.

Application April 6, 1939, Serial No. 84,099

Term of patent 7 years

To all whom it may concern:

Be it known that I, Joseph H. Jacobs, a citizen of the United States and residing in the city of Minneapolis, county of Hennepin, and State of Minnesota, have invented a new, original, and ornamental Design for an Engine Driven Electric Generator Unit, of which the following is a specification, reference being had to the accompanying drawing forming a part thereof, wherein,

Fig. 1 is a front perspective view of an engine

driven electric generator unit showing my new design;

Fig. 2 is an elevational view of the left-hand end;

Fig. 3 is an elevational view of the right-hand end, and

Fig. 4 is a rear elevational view.

I claim:

The ornamental design for an engine driven electric generator unit, as shown.

JOS. H. JACOBS.
